[57] CLAIM

The ornamental design for a utility box for a pickup truck, as shown and described.

DESCRIPTION

FIG. 1 is a perspective view of a utility box for a pickup truck showing my new design;

FIG. 2 is a perspective view thereof with the lid in open condition;

FIG. 3 is an end elevation view thereof, the opposite end being a mirror image of that shown;

FIG. 4 is a front elevation view thereof;

FIG. 5 is a top plan view thereof;

FIG. 6 is a rear elevation view thereof;

FIG. 7 is an end elevation view of a utility box for a pickup truck showing a second embodiment of my new design, the opposite end being a mirror image of that shown;

FIG. 8 is a front elevation view of FIG. 7; and

FIG. 9 is a rear elevation view of FIG. 7.

The top of the second embodiment of the utility box is identical to that of the first embodiment thereof shown in FIG. 5 and the bottom of the two embodiments of the utility box is plain and unornamented.

FIG. 1.FIG. 2.FIG. 3.FIG. 4.FIG. 5.

FIG. 6.
